[57] CLAIM

The ornamental design for a karate shoe, as shown and described.

DESCRIPTION

FIG. 1 is a front perspective view of a karate shoe showing my new design;

FIG. 2 is a bottom plan view with the end of the strap broken away for ease of illustration;

FIG. 3 is a top plan view of FIG. 1;

FIG. 4 is a right side elevational view of FIG. 2;

FIG. 5 is a front elevational view thereof; and

FIG. 6 is a rear elevational view thereof.
